DINING TABLE

Angelo Fasce, Genoa, Italy

Application July 26, 1937, Serial No. 155,767
In Italy August 10, 1936

2 Claims. (Cl. 312—151)

The present invention relates to dining-room tables and it particularly has for an object to provide a table for containing all things necessary for dining service for several persons, the service being controlled by the host who sits at one place at the table and conducts the service without the aid of waiters or other persons.

Further, it is an object to provide a table of the character stated of a simple construction which will be inexpensive to construct and by the use of which table service is reduced to the minimum.

Again, it is an object to provide a table of the character stated with a central part capable of being elevated by the host and having compartments containing the necessary table service, etc., and a base part mounted on a hollow pedestal, and which carries in its periphery a plurality of compartments with suitable drop doors, the central part also comprising a flat rotatable top, an upper section and a lower section, the three parts being mounted on a tubular sleeve that fits telescoped on a tubular post, in which means are provided for raising and lowering the sleeve and its carried parts.

Other objects of the invention will in part be obvious and in part be pointed out hereinafter.

To the attainment of the aforesaid objects and ends the invention still further resides in the novel details of construction, combination and arrangement of parts, all of which will be first fully described in the following detailed description and then be particularly pointed out in the appended claims, reference being had to the accompanying drawings, in which:

Fig. 1 is a side elevation of a table embodying my invention, the central section being raised to a position for serving of the table-ware.

Fig. 2 is a view similar to Fig. 1 with the central section raised fully to a position for serving the food.

Fig. 3 is a vertical section on the line 3—3 of Fig. 1 with the central section in its lowermost position.

Fig. 4 is a horizontal section on the line 4—4 of Fig. 2.

Fig. 5 is a horizontal section on the line 5—5 of Fig. 2.

Figs. 6, 7 and 8 are detail diagrammatic sectional views, illustrating how the wine and water bottles are operated.

Fig. 9 is an enlarged detail section showing how the chain drive is attached to the sleeve of the central table section.

55 In the drawings, in which like letters and

numerals of reference indicate like parts in all the figures, it will be seen that A represents the pedestal of the table, B the fixed part of the table top, and C the central section.

The pedestal A is hollow and has securely 5 mounted centrally therein a hollow post 1 on which is a vertically slidable sleeve 2 and in which post 1 is an endless chain 3 running around two sprockets 4 and 5, one of which, 4, is mounted on a pin or shaft 6 carried within the post 1 and the other, 5, is mounted on a shaft 7 which extends through the post 1 at the bottom and carries another sprocket 8 around which and around a sprocket 9 on a crank shaft 10 another endless chain 11 passes. The crank shaft is mounted 15 in the top B and is conveniently accessible to the host.

The top B has a hollow periphery formed with suitable partitions into a series of compartments 12, each having a drop door 13 hinged at the 20 bottom as at 16. Bottles 14 on slide bases 15 are mounted in the compartments 12 and are so arranged (see Figs. 6 to 8) that when the door 13 is opened and dropped down the bottles 14 may be slid forwardly to expose their necks, so 25 that they may be tilted by the diner to pour the contents thereof without removal of the bottles from their compartments.

The table top B has a central aperture in which fits the turntable 17 which is rotatably 30 mounted by means of the bearing member 18 on the top of the sleeve 2.

The sleeve 2 carries a ring support 19 on which the bottom unit 20 of the central section rests. This section is not rotatably mounted on the 35 sleeve, but is fixed thereto.

The top unit 21 of the central section is rotatably mounted on the sleeve 2 above the unit 20 and directly below the turntable 17.

The part 1 is longitudinally slotted as at 22 to 40 permit passage of the pin or finger 23 carried by the sleeve 2 and attached to chain 3, so that upon turning the crank 10, by means of its handle, the central section of the table may be raised or lowered as desired.

The central section of the table is counterbalanced by weights 24 on cables 25 taking over pulleys 26 and secured to the lower extremity of the central section.

The upper unit 21 of the central section is of 50 box-like form and is divided by radial partitions 27 (see Fig. 5) into a number of compartments (the number depending on the number of persons the table is designed to serve), in which the food to be served is placed. These compartments are 55

preferably closed by suitably constructed panels or doors 28.

The lower unit of the central section is also divided by radial partitions 29 into a like number of sections as the upper unit and by vertical U-shaped partitions 30 forming compartments for individual bottles of wine or liquor. The compartments between adjacent partitions 29 are subdivided by horizontal partitions 31 into several compartments for the storage of dishes and table service for the different courses of the dinner, the upper compartment being designed to receive glasses, cups, condiment holders, etc.

Operation

15 The cooked meal for each person is placed in the food compartments of the top unit 21 of the central section (the serving section) and the required dishes, and table service is arranged in the lower unit of the central section.

20 The guests and host being seated at their respective places around the table, the host turns the crank shaft 10 to raise the central or serving section of the table until the two units are exposed (see Fig. 2). The diners then remove from their respective sectors the dishes and table service for the first course. The host then lowers the inner section to the position of Fig. 1 and the diners remove the food for the first course from the top section. The top unit of the central section being 30 rotatable about its axis, the different compartments may be filled respectively with the food of a single course only. The diners turn the top unit and take out the food and wines of the desired course as they come around to the various 35 positions at the table. After the diners have thus been served the host lowers the central section again to the position of Fig. 3, where it remains until it is desired to serve the next course 40 whereupon the cycle of operations is repeated.

45 At the service of the next course the soiled dishes, etc., of the first course are replaced in the central section, by the diners, and the dishes, etc., for the next course are removed from the same.

From the foregoing description, taken in connection with the accompanying drawings, it is thought that the construction, operation and advantages of the invention will be clear to those skilled in the art to which it appertains. 5

What I claim is:

1. A dining table comprising a hollow pedestal, a table top fixed thereto and having a peripheral set of compartments and a central opening, a central service section fitting within the pedestal 10 and having a turn-table at the top filling said central opening, said central service section including a non-rotatable bottom unit and a rotatable top unit beneath the turn-table, said units being divided by radial partitions into a number of 15 sectors corresponding to the number of diners the table is designed to serve, the top unit's sectors serving as food compartments and the bottom unit's sectors serving as table-service compartments, and means to raise and lower said central 20 section to bring said units above the level of the fixed table top.

2. A dining table comprising a hollow pedestal, a table top fixed thereto and having a peripheral set of compartments and a central opening, a 25 central service section fitting within the pedestal and having a turn-table at the top filling said central opening, said central service section including a non-rotatable bottom unit and a rotatable top unit beneath the turn-table, said units 30 being divided by radial partitions into a number of sectors corresponding to the number of diners the table is designed to serve, the top unit's sectors serving as food compartments and the bottom unit's sectors serving as table-service compartments, and means to raise and lower said central section to bring said units above the level of the fixed table top, said lower unit also having 35 U-shaped vertical partitions at the outer extremities of the radial partitions to form wine-bottle 40 receiving chambers, the remaining parts of the sectors being also subdivided by horizontal partitions into a number of plate-receiving compartments.

ANGELO FASCE. 45
